DESIGN FOR A BILLBOARD

William S. Brede, Minneapolis, Minn.

Application April 22, 1936, Serial No. 62,234

Term of patent 7 years

To all whom it may concern:

Be it known that I, William S. Brede, a citizen of the United States of America, residing at Minneapolis, in the county of Hennepin and State of Minnesota, have invented a new, original, and ornamental Design for a Billboard, of which the following is a specification, reference being had to the accompanying drawing, forming part thereof.

I claim:—

The ornamental design for a billboard, as shown.

WM. S. BREDE.
